FOREIGN PATENT DOCUMENTS

GB 9006574711-0001 * 12/2018

Primary Examiner — L. A. Grabenstetter

(74) Attorney, Agent, or Firm — Foley & Lardner LLP

(57) **CLAIM**

We claim the ornamental design for a bone instrument shank, as shown and described.

DESCRIPTION

FIG. 1 is a front, right perspective view of the claimed design;

FIG. 2 is a rear, right perspective view of the claimed design of FIG. 1;

FIG. 3 is a front view of the claimed design of FIG. 1; FIG. 4 is a rear elevation view of the claimed design of FIG. 1;

FIG. 5 is a right side view of the claimed design of FIG. 1;

FIG. 6 is a left side view of the claimed design of FIG. 1;

FIG. 7 is a top view of the claimed design of FIG. 1; and, FIG. 8 is a bottom view of the claimed design of FIG. 1.

1 Claim, 7 Drawing Sheets
